ABSTRACT OF THE DISCLOSURE

A cleaning device for simultaneously cleaning the dust outlets and the clean-gas outlet in small centrifugal dust separators, which are provided with a central clean-gas outlet tube and a plane end wall having two or more openings located close to the periphery of the separator casing and functioning as outlets for separated dust. The cleaning device consists of an element having one end outside the separator, passing through the outlet tube for clean gas and terminating in branch elements supporting scraping means for clearing dust from the edges of the dust outlet openings.

Background of the invention

Centrifugal separation of dust from dust-laden air or gas by means of cyclones is well known in the prior art. As evidenced from my copending application Ser. No. 553,749 and the corresponding British Patent Number 1,084,646, these cyclones may be formed with a cylindrical portion which is terminated with a plane end wall provided with two or more openings located close to the periphery of the cylindrical portion and functioning as outlets for separated dust. Furthermore, as evidenced from U.S. Patent Number 2,848,066, a cleaning device for cyclones of another type which are provided with only one dust outlet opening located coaxially with the cyclone body, is previously known. This cleaning device consists of a movably-mounted element which extends through both the clean-gas outlet and the dust outlet, the end of said element which is located outside the clean-gas outlet being movably supported by an operator constructed to give an axially-reciprocating action to said element. However, the use of such a conventional cleaning device for simultaneously cleaning the dust outlets and the clean-gas outlets in cyclones described in the above-mentioned British patent, gives rise to difficulties, because cleaning devices for the dust outlet openings which are located in the periphery of the cylindrical portion, tend to interfere with efficient dust separation.

Summary

The present invention relates to an improved cleaning device for small cyclones having two tangential inlets for raw gas and a centrally located outlet tube for discharging clean gas.

The present invention provides a suitable cleaning device for cyclones of the above-mentioned kind, which does not substantially interfere with efficient dust separation, yet which removes accumulated dust from the outlets to prevent clogging.

More particularly, the present invention is characterized in that a cleaning device projects through the dust outlets with branches corresponding in number to the outlet openings, each of which branches being arranged to support a scraping means inserted in and conforming to its respective outlet opening, which scraping means, upon reciprocation of the cleaning element, will remove dust deposited on the edges of the outlet openings, the element also being provided with annular scraping means bearing against the inside of the clean-gas outlet.

2

Drawings

The invention will now be more described with reference to the accompanying drawing figures, wherein:

FIG. 1 is a longitudinal vertical section of a cyclone with a cleaning device according to the invention shown in elevation;

FIG. 2 is a longitudinal horizontal section of the cyclone of FIG. 1; and

FIG. 3 is a transverse section taken along the section 10 3—3 of FIG. 1, with the inlet portion of the cyclone shown in phantom lines.

Description

With reference to the drawings, the cyclone separator 15 comprises a generally cylindrical casing 3 having a pair of tangential inlets 1 for raw dust-laden gases. The inlets 1 introduce the gas with a tangential helical motion into the generally cylindrical shell 3 so that the dust particles are separated from the rotating flow of gas by centrifugal force. The clean gas is discharged from the casing shell 3 by means of a central tube 2 which projects into the shell beyond the tangential inlet. At the opposite end, the shell 3 terminates in a plane end wall 4 which is provided with two openings 5 adjacent to the shell 3 at its junction with the end wall. The incoming dust-laden gas causes a flow toward the end wall 4 which discharges the separated dust through the openings 5 into a channel 12 through which the dust is directed to a suitable collecting means.

In accordance with the invention, a cleaning device 30 is provided for the openings 5 and the central tube 4 to maintain the edges free of dust without impairing the efficiency of the dust-separating means. Outside the clean-gas outlet, there is an operator 7 to which the end of the cleaning element 6 projecting outside the clean-gas outlet 35 is movably connected, so that when the operator is rocked on its pivot as indicated by the arrow in FIG. 1, the element 6 is reciprocated axially within the tube 2. Inside the cyclone, the element extends both through the clean-gas outlet tube 2 and the dust outlets 5. Adjacent the plane end wall 4, the element terminates in two branches 8, which in turn, support scraping means 9 conforming to the outlets 5, and which upon reciprocation of the element, are inserted in the openings 5, for scraping away dust deposited on the edges of the outlets. In order to 45 guide the scraping means 9 through the openings 5, the extensions of the branches 8 bear resiliently against the innermost edges 11 of said openings, and are suitably provided with a width corresponding to the width of the outlet openings. Adjacent the other end of the element 50 within the clean-gas outlet, a scraping means 10 bears against the inside of the outlet tube 2 and consists of a spirally-wound coil.

The invention is, of course, not limited to the above-mentioned embodiment but may be varied within the 55 scope of the invention.

What I claim is:

1. In a cyclonic separator comprising a casing including a shell with a generally cylindrical portion at its inlet end and having two tangential inlets for raw gas, a tube 60 projecting beyond said tangential inlets centrally within said inlet portion to constitute a clean-gas outlet, said casing shell terminating at the opposite end in a plane bottom wall spaced from said outlet tube, and a plurality of dust openings in said bottom wall positioned adjacent 65 the shell at its junction with said bottom wall to serve as outlets for the separated dust; the improvement wherein in said separator includes a cleaning device consisting of an element having one end outside of said casing, a medial portion extending through the clean-gas outlet 70 tube, and terminating in a plurality of branches, each projecting through one of said dust outlet openings, said

element being supported for movement axially within said tube and said outlets, an operator connected to said element to give an axial reciprocating action to said element, a scraping means on each branch inserted in and conforming to its respective outlet opening, which scraping means upon reciprocation of the element, will remove dust deposited on the edges of the outlet openings, and annular scraping means mounted on said element within and bearing against the inside wall of the clean-gas outlet tube.

2. A cleaning device according to claim 1, wherein the parts of the branches projecting through the dust outlets, bear as guiding means against the innermost edges of the dust-outlet openings upon reciprocation of the element.

3. A cleaning device according to claim 1, wherein the annular scraping means bearing against the inside of the clean-gas outlet tube is spirally-wound coil.

5

10

15

4. A cleaning device according to claim 1 wherein each branch is positioned in its associated outlet opening remote from the casing shell, and the scraping means comprises a single loop having an outline conforming to said opening.
